(57) **CLAIM**

The ornamental design for a cylinder housing for air compressor, as shown and described.

DESCRIPTION

FIG. 1 is a front perspective view of a cylinder housing for air compressor showing my new design;

FIG. 2 is a front elevational view thereof;

FIG. 3 is a rear elevational view thereof;

FIG. 4 is a top plan view thereof;

FIG. 5 is a bottom plan view thereof;

FIG. 6 is a left side elevational view thereof;

FIG. 7 is a right side elevational view thereof;

FIG. 8 is a front perspective view thereof, the intermediate cutting line and the orifices depicted by means of broken lines being for illustrative purposes only and forming no part of the claimed design; and,

FIG. 9 is a rear perspective view thereof, the intermediate cutting line and the orifices and the swelling depicted by means of broken lines being for illustrative purposes only and forming no part of the claimed design.
